UNITED STATES PATENT OFFICE.

BENJAMIN F. HILDEBRAND, OF SAN FRANCISCO, CALIFORNIA.

STERILIZER.

1,298,631.

Specification of Letters Patent. Patented Mar. 25, 1919.

Application filed September 13, 1918. Serial No. 254,860.

To all whom it may concern:

Be it known that I, BENJAMIN F. HILDEBRAND, a citizen of the United States, and residing in the city and county of San Francisco, State of California, have invented a new and useful Improvement in Sterilizers, of which the following is a specification.

My invention relates to improvements in sterilizers and consists in the particular construction and arrangements of parts as hereinafter described and claimed.

The primary object of the present invention is to provide an improved, compact and efficient sterilizer.

A further object of the invention is to provide an improved and simplified construction whereby a cheap and durable article may be produced.

I accomplish these several objects by means of the construction disclosed in the drawings forming a part of the present specification wherein like characters of reference are used to designate similar parts throughout the said specification and drawings, and in which—

Figure 1 is a perspective view of my improved sterilizer;

Fig. 2 is a transverse sectional view;

Fig. 3 is a partly broken view in longitudinal section; and

Fig. 4 is a detailed elevation of the separator and support for the heating unit.

Referring to the drawings the numeral 1 is used to indicate the outer one of a pair of nested cylinders and 2 the inner cylinder. The cylinders 1 and 2 are connected at their upper portions of their peripheries by means of a well 3 having apertured side walls to permit the passage of expanded air from between said cylinders 1 and 2.

The well opening 3 is provided between the cylinders 1 and 2 in order to provide an opening into the inner cylinder 2 through which articles to be sterilized may be passed into said inner cylinder 2.

A cover 4 is hingedly mounted above the well opening 3 as at 5, said cover being provided with what I term a condensing plate 6 having depending flanges 7 on all sides thereof which depend into the well opening 3 when the cover 4 is closed whereby condensed moisture may be drained back into the inner cylinder 2.

The cylinders 1 and 2 are retained in spaced relation by means of insulating an-

nular separators 8 having a series of apertures 9 within which apertures are mounted longitudinal conductors 10 to form a heating unit, said conductors 10 being alternately connected at their adjacent ends to form a complete coil. The terminals of the coil are connected to suitable wires 12 passing through an insulating thimble 13 arranged within one end of the outer cylinder 1.

In operation the inner cylinder 2 is partially filled with water and the articles to be sterilized are placed within said cylinder 2 and the water therein.

A current is passed through the conductors 10 to heat the same and said heat, by radiation, heats the water within the cylinder 2.

It is obvious that the air between the cylinders 1 and 2 will expand as the temperature of the said air increases. This expansion of air is partially dissipated through the apertures in the side walls of the well opening 3 and passing into the interior of the said cylinder 2 assists in heating the water therein. As the current is discontinued through the conductors 10 the air is cooled and gradually contracts through said apertures thereby preventing an excessive pressure within the space between the cylinders 1 and 2.

The well opening and hinged cover 4 are normally retained uppermost by means of lateral supports or extensions 14 mounted on the periphery of the outer cylinder 1 and opposite the well opening 3 between said cylinders.

I am aware that the present state of the art discloses heaters comprising nested containers with a heating unit interposed. I therefore do not claim such a combination broadly as my invention, but—

Having thus described my invention, what I claim is—

1. A sterilizer comprising a pair of nested cylinders; a well connecting the cylinders to provide an opening to the inner cylinder; a heating unit interposed between the cylinders; and means for supporting the cylinders in spaced relation and the heating unit between said cylinders.

2. A sterilizer comprising a pair of nested cylinders; a well connecting the cylinders to provide an opening to the inner cylinder; a heating unit interposed between the cylinders; means for supporting the cylinders in

spaced relation and the heating unit between said cylinders; and lateral extensions secured at each end of the outer cylinder and opposite the well to retain said well uppermost.

3. A sterilizer comprising a pair of nested cylinders; a well connecting the cylinders at the top portions thereof to provide an opening into the cylinder; a suitable cover hingedly mounted above the well; a condensing plate secured to the under side of the cover and having depending flanges to drain condensed moisture into said well; annular insulators mounted between the ends of the cylinders to retain and support said cylinders in spaced relation; and a heating unit mounted between said annular insulators.

4. A sterilizer comprising a pair of nested cylinders; a well connecting the cylinders at the top portions thereof to provide an opening into the inner cylinder; a suitable cover hingedly mounted above the well; a condensing plate secured to the under side of the cover and having depending flanges to drain condensed moisture into said well; annular insulators mounted between the ends of the cylinders to retain and support said cylinders in spaced relation; a heating unit mounted between said annular insulators; and lateral extensions mounted upon each end of the outer cylinder and opposite the well to retain said well uppermost.

5. A sterilizer comprising a pair of nested cylinders; a well connecting the cylinders

between portions of their peripheries, said well having apertured walls to permit the passage of air to the space between the said cylinders; a suitable cover hingedly mounted above the well; a condensing plate secured to the under side of the cover and having flanges depending into the well to convey condensed moisture from said plate into the inner cylinder; apertured annular insulators mounted between the ends of the cylinders to retain the same in spaced relation; and a heating unit mounted within the apertures of said insulators.

6. A sterilizer comprising a pair of nested cylinders; a well connecting the cylinders between portions of their peripheries, said well having apertured walls to permit the passage of air to the space between said cylinders; a suitable cover hingedly mounted above the well; a condensing plate secured to the under side of the cover and having depending flanges on all sides thereof depending into the well to convey condensed moisture from said plate into the inner cylinder; apertured annular insulators mounted between the cylinders to retain the same in spaced relation; a heating unit mounted within the apertures of said insulators; and lateral extensions mounted upon each end of the outer cylinders and opposite the well to retain said well uppermost.

In witness whereof I hereunto set my signature.

BENJAMIN F. HILDEBRAND.
